UNITED STATES PATENT OFFICE.

WILLIAM H. HOLMES, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND.

CASH REGISTER.

Application filed March 10, 1921. Serial No. 451,280.

This invention relates to cash registers and more particularly to means for converting a cash register of the type having an incomplete bank of penny or unit keys and adapted to register amounts involving five cents or more multiples thereof commonly known to the trade as "bar" machines into cash registers of general usage having a complete bank of penny or unit keys, any one of which serves to release the operating mechanism together with means for releasing such operating mechanism when no penny or unit key is to be operated.

An object of the invention is to provide an improved form of connecting means between any bank of value or identity determining elements and a special release key whereby the operating mechanism may be unlocked by the operation of any key of the related bank independently of the operation of the special key or may be unlocked by the operation of the special key independently of the operation of any key of such related bank of keys.

In particular, the object of the invention is to provide simple and effective means which may be readily incorporated into existing machines for converting such machines from a limited capacity to a wider range of operation.

A further object of the invention is to provide an improved form of key detent and means for operating the same and to provide improved means for actuating the locking detents of the cash register mechanism to release positions.

With the above primary and other incidental objects as will more fully appear in the specification the invention consists of the features of construction, the parts and combination thereof and the mode of operation or equivalents as hereinafter described and set forth in the claims.

Referring to the drawings, Fig. 1 is a side elevation of a portion of a cash register embodying the present invention. Fig. 2 is an elevation of a bank of registering mechanisms viewed from the side opposite that shown in Fig. 1. Fig. 3 is a detail view illustrating the relation of parts viewed from the left in Fig. 2. Fig. 4 is a detail perspective view of the key detent which is added to the existing mechanism to effect the new result. Fig. 5 is a detail view of a

modification of the detent control means shown in Fig. 1. Fig. 6 is a front elevation of the tens and units banks of keys in their original form and relation prior to being converted. Fig. 7 is a similar view of the same banks of keys after the embodiment therein of the invention forming the subject matter hereof.

Like parts are indicated by similar characters of reference throughout the several views.

For illustrative purposes the present invention has been shown embodied in a cash register of the type shown and described in Patent No. 483,511 issued September 27, 1892 to Hugo Cook, Patent No. 580,378 issued April 18, 1897 to Joseph P. Cleal and Frank A. Reinhard, Patent No. 690,554 issued January 7, 1902 to Frank H. Bickford, Patent No. 724,378 issued March 31, 1903, and Patent No. 949,884 issued February 22, 1910 to Joseph P. Cleal, and Patent No. 996,814, issued July 4, 1911 to E. J. Von Pein, and reference may be had to the said patents for a more detailed description of the registering and operating mechanism. The cash register mechanism shown in the said patents is of the type known as "two motion," that is, the keys comprise setting elements or stops which are first depressed to determine the record or registration to be effected and to release or unlock the normally locked operating mechanism. This operating mechanism after being unlocked by the operation of the setting element is actuated by a crank or suitable driving mechanism.

Inasmuch as the registering mechanism per se forms no part of the present invention it has been illustrated only in fragmentary form.

The operation of the machine to which the present improvements are applied is substantially the same as that of the machine shown in the above mentioned Letters Patent, but for convenience may be briefly stated as follows: The machine comprises a plurality of banks of keys 1 and adjunct parts shown in Figs. 2 and 3, any one of which keys when depressed serves as a stop for a differentially movable rocking segment 2. The segment rack 2 receives its rocking movement from a sector 3, to which it is automatically coupled and un-

coupled in a manner well known in the art and fully set forth in the above enumerated Letters Patent. The sector 3 is rigidly mounted upon a rock shaft 4 having bearings in the side frames 5 of the structure. An oscillatory movement is transmitted to the rock shaft 4 by any suitable actuating means. The teeth of the rack segment 2 mesh with a gear pinion not shown in the drawings, through the medium of which the differential movement of the segment 2 is transmitted to indicating and totaling mechanisms in a manner well known in the art and needing no description here, but for which reference is to be had to the aforementioned prior Letters Patent.

The plunger keys 1 which are arranged in radial position are depressible against a spring 6. The inner ends of the key stems 20 are beveled or cammed as at 7 for engagement with the inclined walls 8 of notches formed in an oscillatory detent plate 9 pivoted loosely upon the rock shaft 4 as shown in the patent to Chambers, 1,062,767 granted May 27, 1913. The segmental detent 9 is oscillated upward by the depression of any one of the series of keys 1 through the interengagement of the cammed end 7 with an inclined mold 8. This upward movement of the detent plate 9 releases a latch bar 10 which is projected rearward by a retracting spring 11 thereby carrying a locking shoulder 12 of said latch bar beneath the lower end of the detent plate 9 to lock the detent plate in its elevated position where it engages and retains the depressed or operated key and prevents the operation of any other keys of the bank until released at the completion of the operation. As ordinarily constructed and as shown in the prior patents referred to the detent plate 9 carries a stud which in the movement of the detent plate effects the release of the normally locked operating mechanism. In Fig. 2 there is shown at the upper end of the detent 43 a hole 13 from which such stud has been removed. The locking devices controlled by such stud upon the movement of the detent plate 9 in the usual construction comprise among other elements a rock shaft 16 (Fig. 1) journaled in the side frames and provided with a rock arm 17 engaging with the aforementioned stud to control the oscillation of the shaft 16. The present invention 50 pertains primarily to the transfer of this control stud from the key detent plate 9 to an auxiliary key detent hereinafter described. The locking mechanism controlled by the rock shaft 16 may be of various forms 55 of construction. For instance in the aforementioned patent to Von Pein 996,814, the rock shaft 16 of the present construction is identified in the Von Pein construction as rock shaft 58 controlling a link 55 connected to an arm 59 upon a shaft 60 which in turn

carries a rock arm 61 connected at 62 to a locking detent 37. The last mentioned reference characters it being understood, are those of the Von Pein patent. In the Von Pein patent the rock shaft identified as 58 70 and corresponding to the shaft 16 of the present construction is spring actuated so that it moves automatically upon the disengagement of the stud carried by the detent plate from the arm 73 of the Von Pein patent which corresponds to the arm 17 of the present construction. 75

In the patent to Cleal 949,884 there is shown a different type of locking mechanism illustrated in Figs. 13 and 14 in which the rock shaft 28^b of Cleal patent corresponding to the rock shaft 16 of the present construction is actuated by the engagement of the stud with a cam surface upon the rock arm 52^b to disengage a locking detent 45^b 85 from the notched disc. So far as the present invention is concerned, it is immaterial just what locking mechanism is employed as reference to the Von Pein and Cleal patents is made for the purpose of showing different types of detent mechanism operated from and under the control of the rock shaft 16, and rock arm 17 of the present construction.

As thus far described except for the reference to the transfer of the controlling stud from the key detent plate 9 to an auxiliary key detent, the construction is one well known in the cash register art and forms no part of the present invention, but is shown in the drawings and heretofore referred to merely for the purpose of illustration, and in order that the relation of the present invention to the cash register mechanism may be better and more easily understood. 105

Referring now particularly to the subject matter of the present invention it is to be understood that there are now in existence great numbers of cash registers known to the trade as "bar" machines, which have only one value key in the units or penny bank, namely, the five cent key, and in addition thereto a non-registering key having no numerical value, but which is merely a release key. In such machines either of 110 these keys that is to say, the five cent key or the release key when operated elevates the key detent plate 9 and moves the control stud before mentioned into relation with the rock arm 17 to effect the unlocking of the 115 mechanism. These machines were originally intended to register only multiples of five cents. In the event that the amount to be registered included five cents such as twenty-five cents, fifty-five cents, a dollar and 120 thirty-five cents, etc., the depression of the five cent key which in such case is the only registering key in the penny or cent bank, would effect the elevation of the key detent plate, and the unlocking of the machine. In 130

the event, however, that the sum to be registered did not terminate in five cents, but was a ten or multiple of ten as twenty cents, seventy cents, one dollar, etc., then the special release non-registering key would be operated to likewise actuate the key detent plate and effect the unlocking of the mechanism, exactly as in the case of the five cent key. In other words, the machine is released for operation only upon the depression of either a key in the units bank or the special release key. Such a key-board arrangement has been shown in Fig. 6 in which 18 is the tens bank of keys and 19 is the pennies or units bank. The latter bank of keys in this original form contains a single value key 20 of the five cent denomination and a non-registering release key 21, the depression of either of which will serve to rock the key detent plate and so effect the release of the mechanism.

In converting a machine of the "bar" type, having the limited key arrangement shown in Fig. 6, the key frame or support is removed from the machine and if not already provided by the manufacturer, additional key guides or openings for the stems of the plunger keys are milled or otherwise formed in this frame. The frame is then provided with a full complement of value keys from one to nine inclusive in the pennies or units bank 19. Inasmuch as machines of this type as originally constructed are dependent on the operation of the key detent plate of the pennies or units bank for the release of the mechanism, some special release key must be provided for use in instances where the amount does not involve pennies or units. Such release key is necessary to perform the functions of the key 21 of Fig. 6. To this end there is provided upon the converted machine a special release key 22 mounted in a key guide or bracket 23 secured to the side of the frame of the machine. This key 22 is of the usual plunger type and is depressible against a spring 24.

The control stud hereinbefore referred to as carried by the oscillatory key detent plate 9 in the original construction is transferred from the key detent plate 9 to an auxiliary oscillatory key detent plate 25, upon which the control stud is shown at 26. The key detent 25 is loosely journaled upon the main shaft 4. In the original construction there is usually found upon the inner face of the side frame 5 a boss indicated by dotted line at 27 in Fig. 3. This boss is removed in the conversion of the machine and affords ample space for the insertion of the key detent 25 intermediate of the side frame 5 and the oscillatory key detent plate 9. The key detent 25 is provided with an inturned lip or flange 28 which overhangs the rear edge of the key detent plate 9 and lies in the path of the detent plate whereby the

oscillation of the detent plate 9 by the manipulation of any value keys of the cents or units bank will also effect the oscillation of the key detent 25 in unison with the movement of the detent plate. The stud 26 carried by the detent plate 25 bears the same relation to the rock arm 17 as when carried directly upon the detent plate 9 in the original construction. In addition to the in-turned lip or flange 28, the key detent 25 carries an outwardly projecting flange or lip 29 extending into the path of movement of the depressible special release key 22. The construction is such that upon the depression of the special release key 22 to unlock the machine for registration of sums involving no pennies or cents, the key detent 25 will be oscillated independently of the key detent plate 9, carrying with it the control stud 26 which will perform its function in effecting the release of the mechanism although the key detent plate 9 by which it is ordinarily and originally carried remains entirely at rest. It is this simple construction affording means for shifting the control stud 26 independently of the key detent plate by which the stud is normally and originally carried which enables machines of the "bar" type to be quickly and very cheaply converted into "regular" machines of full capacity. The oscillation of the key detent 25 is effected against the tension of a retracting spring 30. As can be seen in Fig. 1, the rearward oscillation of the key detent 25 whether the same is effected in unison with the oscillation of the key detent plate 9 under the influence of the value keys of the pennies or units bank, or effected independently of the movement of the key detent plate 9 under the influence of the special release key 22, carries the control stud 26 beyond the end of the stop finger 31, and moves an arm 32 also carried by the arm 17, clockwise, whereupon a lock arm 17 is oscillated upwardly by a spring (not shown) causing the control stud 26 to enter between the ends of the stop finger 31 and the rocker arm 32. This movement of the arm 17 and oscillation of the shaft 16 operates through a train of mechanism fully described in the aforementioned patent to Von Pein comprising the link 55, rock arm 59, shaft 60, and arm 61 of the Von Pein construction to actuate the locking link 37 of said construction.

As shown in Fig. 5 the rearward oscillation of the key detent 25 carrying the control stud 26 whether such movement is effected in unison with the movement of the key detent plate 9 under the influence of the value keys of the pennies or units bank or is effected independently of the key detent plate 9, under the influence of the special release key 22, carries the stud 26 into engagement with the beveled or inclined face of the rock arm 125

52^b of the Cleal construction mentioned to elevate this rock arm and rock the shaft 16 thereby depressing the locking nose 45^b of the detent arm 41^b out of the notch 46^b of the locking disc.

While the present invention is a comparatively simple addition to existing machines of a certain type, it is nevertheless far reaching in effect and very useful in its function 10 in that it not only enables salvaging of vast numbers of cash registers for which there is now little or no demand or use, but the construction shown is a valuable and efficient adjunct to these structures and may be 15 incorporated at the time of manufacture with beneficial results. Since it is of value when incorporated in new structures at the time of manufacture, as well as affording means for converting obsolete machines into 20 usable cash registers, the invention is not necessarily limited to the latter use only.

From the above description it will be apparent that there is thus provided a device 25 of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute 30 the invention has been described in language more or less specific as to structural features, it is to be understood that the invention is not limited to the specific details shown, but that the means and construction herein dis-

closed comprise but one of several modes of putting the invention into effect, and the invention is therefore claimed in any of its 40 forms or modifications within the legitimate and valid scope of the appended claims.

Having thus described my invention, I claim:

1. In a cash register, the combination of 45 a bank of amount keys, a supporting frame therefor, a bracket fast to said frame, a single key mounted in said bracket, and a segmental plate having bent portions extending at right angles thereto adapted to co-operate with said single key or said amount keys to release the machine.

2. In a cash register, the combination of 50 a bank of amount keys, a supporting frame therefor, a bracket fast to said frame, a single key mounted in said bracket, a segmental plate adapted to be actuated by said amount keys, a second segmental plate adapted to be actuated by said single key, and means on said second plate adapted to be engaged by said first plate upon depression of one of said amount keys.

3. In a cash register, the combination of 55 a bank of amount keys, a supporting frame therefor, a bracket fast to said frame, a single key mounted in said bracket, a plate adapted to be actuated by said amount keys, a second plate adapted to be actuated by said single key, and an ear on said second plate projecting into the path of said first plate to cause movement of the second plate upon depression of an amount key.

In testimony whereof I affix my signature.

WILLIAM H. HOLMES.
